UNITED STATES PATENT OFFICE.

GEORGE C. THOMAS, JR., OF ELIZABETH, NEW JERSEY, ASSIGNOR TO THE THOMAS & BETTS CO., OF ELIZABETH, NEW JERSEY, A CORPORATION OF NEW JERSEY.

CABLE CONNECTER.

Application filed January 22, 1924. Serial No. 687,781.

This invention relates to combination outlet boxes and cable connectors, and more particularly to connectors for use in anchoring electric cables or conduits to electric box fixtures, such as outlet boxes, switch boxes, cable boxes, and the like.

An object of the invention is to produce an improved cable connector of simple structure capable of being manufactured either by stamping the connector from sheet metal or by casting it and which requires a small quantity of material. Likewise it is an object to produce a cable connector which positively functions to rigidly fasten a cable to said box, as well as produce a cable connector which fits standard round knock-out holes in the boxes of present-day use; and one important feature of my connector resides in the fact that it simultaneously straddles the box wall or knock-out opening and the cable, and has means for setting up a simultaneously anchoring relation jointly with the cable and box.

The accompanying drawing illustrates a preferred form of the invention, the construction of which may be varied or modified without departing from the scope and principle of my invention.

Figure 1 illustrates a top open view of the cable connector shown assembled in a box securing a cable thereto; and Figure 2 shows an outside elevation thereof.

Figure 3 illustrates a cross sectional view taken on the line 3—3.

Figure 4 illustrates an inside elevation of two cable connectors assembled in a box. The left-hand connector is loosely retained in the box knock-out and shows the angular position thereof prior to tightening up the connector. The right-hand connector shows the position thereof after having been tightened up to fasten the cable and connector in the box.

Figure 5 shows a cluster view of the connector in front, side, and bottom elevations.

Referring now more particularly to the drawings and with reference to the structure of the connector itself as shown in Figure 5, there is illustrated a connector of such design as may be manufactured if desired by the stamping and drawing process and resulting in the production of a connector from sheet metal and having flat plate abutment por-

tions. This connector essentially comprises a substantially U-shaped device with spaced inner and outer plates or leg parts; and an outer abutment or bearing plate 7 is made substantially narrower than the diameter of the box knock-out hole H punched in the usual run of boxes B in order that the portion 7 be inserted from the inside of the box out through the knock-out and bear against the outside wall of the box. At the upper end of the abutment plate 7 there is formed an offset web or portion 8 integrally joining with a broad inner bearing or abutment plate 9 adapted to abut against the inner wall of the box. The abutment plates 7 and 9 are parallel and offset one from the other to permit the wall of the electric fixture box wall to rest movably therebetween. An aperture or cable receiving hole 10 is punched through the composite opposite plates 7 and 9; and in fact the said hole 10 is punched through the portion 8 as well, thereby forming the portion 8 into the spaced connecting strips 8 by which the inner and outer abutment plates 7 and 9 are joined together.

The inner end of the plate 9 is bent outwardly as at 11 and downwardly to form a bushing plate 12. The plate 12 is punched and drawn to provide a bushing 14 through which cable wires W are passed, and the wires are protected from wear or abrading action by the ovoidal curve swedged into the bushing 14. The lower end of the plate 12 is made with a rounded surface-bearing or lifting nose 15 which acts to force the connector radially or laterally of the axis of the box knock-out hole H as will be described. An ear 16 is turned outwardly from the plate 12 and carries a pressure screw 17. It is observed how the connector portion 11 spaces the abutment plates 7—9 from the plate 12, and the connector is made in this manner in order that an adequate length of cable be inserted and gripped against the exposed box hole edge.

In assembling the parts, a connector is first attached to the box by introducing the outer abutment plate 7 through the knock-out H, and the connector is then placed in an angular position as shown at the left in Figure 4 with the pressure screw partly screwed out from the ear 16. The lifting lug or bearing nose 15 is thus disposed at an angle with the box wall B, the result of

which permits the cable C to be easily inserted through the hole 10 of the plate connector and the knock-out hole H of the box inasmuch as the hole 10 lies within the circumference of the box knock-out H. The cable wires W are drawn through the bushing 14 with the inner end of the cable C abutting the plate 12. The pressure screw 17 is now screwed downwardly against the bottom of the box wall B which causes the nose 15 to slide along the box, causing rotary as well as a radial motion of the connector relatively to the box, bringing it into vertical position as shown at the right in Figure 4.

This compound movement of the plate develops considerable force as the pressure screw 17 is being turned, the connector device rotating within the box hole H as well as sliding upwardly away from the wall B. This compound radial and rotary movement brings the lower edge of the hole 10 tightly up against the cable C causing the upper edge of plate 7 to pinch into the cable driving it up against the upper opposite edge of the box opening until the box edge H burrs into the cable wall tightly clamping it; and at the same time the edge of the connector hole 10 burrs or embeds itself into the cable which immovably anchors the cable and box together. The outer abutment plate 7 covers the exposed portion of the box hole H below the cable, and the upper remaining area of the box hole is covered from the inside by the inner bearing plate 9 thus producing a sealed box hole.

The abutment 7 is small enough to pass through the box hole H while the abutment 9 may to advantage be larger than the box hole. In this way one part of the connector is outside the box wall while another part is inside. The box wall itself rests between the two spaced abutments, i. e. the box hole edge H itself rests between the spaced abutments 7 and 9. The connector portion 8 and the general plan of construction leaves a portion of the box hole edge exposed and the cable C is gripped against and between an exposed portion of the box hole edge and the upper edge of the plate 7.

I have therefore produced a connector which fits into a box hole and anchors itself in the hole against longitudinal displacement by reason of the abutment plates. The screw 17 mounted on the connector forces an edge of the connector against the cable which causes a gripping action to take place thereby fixing the cable firmly against the exposed box hole edge.

Furthermore, the screw is mounted in the connector at an angle to the cable and box hole axis and thus impresses the necessary relative lateral motion between the connector and box hole edge to grip the cable

between said connector and box hole edge. 65

What is of further consequence; the screw 17 or other rotatable members are mounted in the connector to the side of the cable so the screw is easily reached by a screw driver. The lifting or bearing nose 15 when needed is 70 located on the other side of the cable, i. e. the cable C is between the screw 17 and nose 15. It follows that the screw itself reacts against the box wall to force the connector or slide it laterally along the box wall which 75 grips the cable C between the exposed box hole edge and the hole edge 10 of the connector. At the same time the abutment plates 7 and 9 cover over the box hole H to close the box against entry of dirt and plaster incident to building operations.

It is observed that the screw may be mounted parallel to the inside and outside abutment cover plate 7-9 which therefore causes said screw to act against the box wall and forcibly slide the plates and particularly move the edge 10 of the connector hole 10 relatively to the box hole edge H. In other words there is the box hole edge H and adjacent thereto is the connector hole edge 10. 90 Together these two rather sharp thin edges encircle the cable C, and the rotatable member 17 acts to forcibly produce relative approach and closing together of these two edges which thus pinches and grips the cable therebetween.

The connector hole 10 is made through the three portions, namely the abutment plates 7 and 9 and the off-set 8 as well. Thus the thin edged hole 10 characteristically is clearly inside the box, outside the box, and through the box hole H, all one and at the same time, and this peculiar arrangement means that two hole edges 10 and H contract and squeeze around the cable C to fix it firmly in the box. 105

The connector is positive in function, simple to apply, and is inexpensive to manufacture.

What I claim is:—

1. Cable and box connecting means comprising, a box with a hole, a connector to receive a cable and of such size as will fit into said box hole, said connector including spaced abutment means in between which rests the box wall and formed to expose a portion of said box hole edge directly to a cable placed therein, and means mounted on the connector and movable relative thereto substantially at right angles to the cable axis and bearing on the box wall to force the connector laterally relative to said box hole to grip the cable between said connector and exposed box hole edge. 115

2. A device as covered in claim 1 but characterized by making the connector and abutment means of sheet metal with a hole therein through which projects and against

the edge of which lies the cable, and the abutments are flat plates which cover over the box hole around the cable.

3. Cable and box connecting means comprising, a box with a hole, a connector to receive a cable and of such size as will fit into said box hole, said connector including spaced abutment means in between which rests the box wall and formed to expose a portion of said box hole edge directly to a cable placed therein, and a screw mounted on the connector at an angle to the axis of the cable and bearing against the box wall forcing the connector to move laterally in relation to said box hole to grip the cable between said connector and exposed box hole edge.

4. A device as defined in claim 2 wherein the connector is made entirely of sheet metal thereby causing the abutment means to assume the form of flat plates spaced apart, and an ear out turned from the flat plate connector on which the screw is mounted.

5. Cable and box connecting means comprising, a box with a hole, a connector to receive a cable and of such size as will fit into said box hole, said connector including spaced abutment means in between which rests the box wall and formed to expose a portion of said box hole edge directly to a cable placed therein, a screw mounted on the connector on one side of the cable and adapted to bear against the box wall to move the connector in relation to the box, and a bearing nose on the connector on the other side of the cable sliding against the box wall forcing the connector laterally to grip the cable between the connector and exposed box hole edge.

6. A device as defined in claim 5 wherein the connector is fashioned from sheet metal with a cable receiving hole therein, and the edge of said connector hole grips the cable part of the way therearound while the edge of the box hole grips the cable the other part of the way therearound.

7. A connector including a portion of such size as will fit into a box hole, said connector including spaced abutments adapted to receive a box hole edge therebetween and formed to expose a portion of said box hole edge, and means mounted on the connector and movable relative thereto substantially at right angles to the axis of a box hole and adapted to bear against a box.

8. A connector including a portion of such size as will fit into a box hole, said connector including spaced abutments adapted to receive a box hole edge therebetween and formed to expose a portion of said box hole edge, and a screw mounted on the connector at right angles to the axis of a box hole and adapted to screw against the wall of a box to move the connector laterally in relation to the box hole.

9. A connector as defined in claim 8, but stamped from sheet metal, thereby forming said abutments into flat plates, which plates overlie and cover the box hole around a cable.

10. A connector including a portion of such size as will fit into a box hole, said connector including abutments spaced apart a distance equal to the thickness of a box wall and formed to expose the edge of a box hole and including a cable receiving hole, a screw mounted on the connector at an angle to the cable opening, and a bearing nose included on the connector which cooperates with the screw to move the connector in a box hole.

11. A connector as defined in claim 10 but made entirely of sheet metal thus forming said abutments into plate portions and forming the bearing nose of sheet metal with a rounded end to ride along a box wall surface.

12. A connector including a portion of such size as will fit into a box hole, said connector including abutments spaced apart a distance equal to the thickness of a box wall and formed to expose the edge of a box hole and including a cable receiving hole, a screw mounted in the connector to one side of the cable receiving hole so the screw is easily reached, and a bearing nose included on the connector on the other side of cable receiving hole.

13. A connector as defined in claim 10 but made entirely of sheet metal which forms said abutments into spaced plates, and one of which is too large to pass through a box hole.

14. A connector as defined in claim 10 but made entirely of sheet metal which forms said abutments into spaced plates, one of which is too large to pass through a box hole, and a bushing punched in a plate portion included on the connector and held in spaced relation from one of the abutment plates by an integral part parallel to the axis of the cable receiving hole.

15. A connector embodying two parallel plates fashioned from a single stamping and substantially U-shaped in side elevation, one of the plates small enough to pass through a box hole and having an off-set which forms of it two spaced abutment plates themselves parallel in between which fits a box wall with the usual cable hole, the off-set portion having a cable hole, and a screw mounted on the other plate parallel to the abutment plates.

16. A connector as defined in claim 15 wherein a bushing is formed in the plate carrying the screw.

17. A connector embodying two parallel plates fashioned from a single stamping and substantially U-shaped in side elevation, one of the plates small enough to pass

- through a box hole and having an off-set portion which forms of it two spaced abutment plates themselves parallel in between which fits a box wall with the usual cable hole, a cable hole in the off-set portion, a bearing nose included on one end at one corner of one plate, a screw mounted parallel to said abutment plates on the same plate at the other corner thereof which spaces it from the bearing nose, and said last named plate including a wire opening disposed substantially between the bearing nose and screw.
18. A connector comprising a plate with an off-set portion which fashions the plate into two parallel abutment portions spaced apart about equal in distance to the thickness of a box wall, said plate having a cable receiving hole formed with portions thereof in the off-set and in the two spaced abutment plates, said plate being formed to fit into a box hole with the cable receiving hole registering with the box hole and with the two spaced off-set abutments disposed on either side of the box wall, and means to forcibly move the plate laterally in relation to the box hole.
19. A connector as defined in claim 18 wherein one of the parallel abutment portions is too large to pass through a box hole.
20. A connector comprising a plate having an off-set forming parallel portions spaced apart a distance about equal to the thickness of a box wall, one portion formed small enough to pass through a box hole, and one portion of the plate adapted to be disposed inside of and parallel to a box wall and the other portion outside of and parallel to a box wall, said plate having a cable receiving opening extending into that portion which is inside a box, which opening is adapted to register with a box hole, said cable receiving opening being partly defined by an edge on the outside portion to support a cable received through the connector, and a screw threaded thru the connector adapted to bear against a portion of a box to move the connector to grip a cable between the box hole edge and that edge of said cable receiving opening which is defined aforesaid on the outside portion.
21. A cable connector comprising a member, a portion of which is suitable in size to fit thru a box hole and formed to expose a portion of said box hole edge directly to a cable, said portion being adapted to support and bear against that side of a cable which is opposite the exposed box hole edge, and said connector and portion having spaced means, by which the connector is guided and retained in a box hole, while said means move in relation to said box hole edge, and a screw mounted on that portion of the connector which is adapted to be placed inside a box and also mounted on the same side of the connector which includes the aforesaid portion adapted to support and bear on the cable, and said screw being adapted to produce a reaction between the connector and box to cause movement of the connector laterally relative to the box hole to grip a cable between the exposed box hole edge and said portion.
22. A connector comprising, a portion suitable in size to fit into a box hole and formed to expose a portion of a box hole edge directly to a cable placed therein, and including spaced means, by which the connector is guided and retained in a box hole, while said spaced means move in relation to said box hole edge, and a screw mounted on the connector at an angle to the connector and cable axis and adapted to react against a box portion to move the connector laterally relative to a box hole to grip a cable between the exposed box hole edge and connector.
23. A connector comprising, a portion suitable in size to fit into a box hole and formed to expose a portion of a box hole edge directly to a cable placed therein, and including spaced means, by which the connector is guided and retained in a box hole, while said spaced means move in relation to said box hole edge, a bearing nose included on the connector and having a rounded bearing surface which slidably engages a box portion, and a screw mounted on the connector adapted to react against the box portion to cause the bearing nose to slide and thereby move the connector laterally relative to a box hole to grip a cable between the exposed box hole edge and connector.
24. A connector comprising, a portion suitable in size to fit into a box hole and formed to expose a portion of a box hole edge directly to a cable placed therein, and including spaced means, by which the connector is guided and retained in a box hole, while said spaced means move in relation to said box hole edge, and a screw mounted on that connector portion which is adapted to be placed inside of a box and adapted to react against an inside box portion to move the connector laterally relative to a box hole to grip a cable between the exposed box hole edge and connector.
25. A connector comprising, a portion suitable in size to fit into a box hole and formed to expose a portion of a box hole edge directly to a cable placed therein, and including spaced means, by which the connector is guided and retained in a box hole, while said spaced means move in relation to said box hole edge, a bearing nose included on the connector and having a rounded bearing surface which slidably engages a box portion, and a screw mounted on that connector portion which is adapted to be placed inside of a box and adapted to react against the inside

box portion to cause the bearing nose to slide and thereby move the connector laterally relative to a box hole to grip a cable between the exposed box hole edge and connector.

- 5 26. A connector comprising, a portion suitable in size to fit into a box hole and formed to expose a portion of a box hole edge directly to a cable placed therein, and including spaced means, by which the connector is guided and retained in a box hole, while said spaced means move in relation to box hole edge, a bearing nose included on the connector and having a rounded bearing surface which slidably engages a box portion, an ear included on the connector and spaced from the bearing nose, and a screw threaded thru the ear adapted to react against the box portion to cause the bearing nose to slide and move the connector laterally relative to the box hole to grip a cable between the exposed box hole edge and connector.

27. A connector comprising a member, a portion of which is suitable in size to fit thru a box hole and so formed as to expose a portion of said box hole edge directly to a cable placed therein, and including spaced means, by which the connector is guided and retained in a box hole, while said means moves in relation to said box hole edge, a screw threaded into the connector adapted to produce a reaction between the connector and the box to impart one motion to the connector, and means included on the connector which slides, by operation of the screw aforesaid, in relation to and in engagement with a box portion to impart another motion to the connector to grip a cable between the exposed box hole edge and connector.

40 28. A connector comprising a member, a portion of which is suitable in size to fit thru a box hole and so formed as to expose a portion of said box hole edge directly to a cable placed therein, and including spaced means, by which the connector is guided and retained in a box hole, while said means moves in relation to said box hole edge, operating means carried on the connector adapted to produce reaction between the connector and box which rotates the connector, and means included on the connector which slides, by action of the aforesaid operating means, in relation to and in engagement with a box portion to impart lateral motion to the connector with respect to the axis of the box

hole to grip a cable between the exposed box hole edge and connector.

29. A connector comprising a member, a portion of which is suitable in size to fit thru a box hole and so formed as to expose a portion of said box hole edge directly to a cable placed therein, and including spaced means, by which the connector is guided and retained in a box hole, while said means moves in relation to said box hole edge, a projecting member included on the connector and having a curved engaging surface adapted to slide against a box portion, and a screw threaded thru the connector the end of which screw is adapted to react against a box portion to impart sliding movement to the projecting member relative to the box, which results in forcibly moving a cable laterally relative to and against an exposed box hole edge and gripping it there.

30. A cable connector comprising a member of suitable size to fit into a box hole and so formed as to expose said hole edge directly to a cable received therein, spaced abutments included on the connector by which both sides of a box wall are engaged by the connector when it is in place, a screw threaded thru and carried on the connector and adapted to produce a reaction between the box and connector by which the connector abutments are held rigidly in place on both sides of a box wall and to simultaneously force a cable against the exposed box hole edge, and said screw being carried on that connector portion which is adapted to be placed inside of the box.

31. A cable connector comprising a member of suitable size to fit into a box hole and so formed as to expose said hole edge directly to a cable received therein, spaced abutments included on the connector by which both sides of a box wall are engaged by the connector when it is in place, and operating means, carried on the connector, adapted to produce a reaction between the box and connector by which the connector abutments are held rigidly in place on both sides of a box wall and to simultaneously force a cable against the exposed box hole edge, and said operating means being carried on that connector portion which is adapted to be placed inside of a box.

In testimony whereof I affix my signature.
GEORGE C. THOMAS, JR.
